US00D574677S

(12) **United States Design Patent**
Broadstone

(10) **Patent No.:** **US D574,677 S**
(45) **Date of Patent:** **** Aug. 12, 2008**

(54) **PLANTING TOOL**

(76) Inventor: **Daniel L. Broadstone**, 1008 Fox
Hunters Point, New Albany, IN (US)
47150

(**) Term: **14 Years**

(21) Appl. No.: **29/272,316**

(22) Filed: **Feb. 6, 2007**

(51) **LOC (8) Cl.** **08-01**

(52) **U.S. Cl.** **D8/1**

(58) **Field of Classification Search** **D8/1;**
111/115, 89, 99, 98; 172/21

See application file for complete search history.

(57) **CLAIM**

The ornamental design for a planting tool, as shown and described.

DESCRIPTION

FIG. 1 is a perspective view of the planting tool showing my new design;

FIG. 2 is a front view thereof;

FIG. 3 is a rear view thereof;

FIG. 4 is a right side view thereof;

FIG. 5 is a left side view thereof;

FIG. 6 is a bottom view thereof; and,

FIG. 7 is a top view thereof.

The broken lines showing the retaining pin for the width adjustment mechanism are for illustrative purposes only and form no part of the claimed design.
